COMBINED CARRYING BAG AND RACKET CASE

Samuel N. Glantz and Milton Glantz, both of 1127 W.
Division, Chicago, Ill. 60622

Filed Oct. 21, 1970, Ser. No. 25,593

Term of patent 14 years

Int. Cl. D3—01

U.S. Cl. D87—1

FIG. 1

FIG. 2

FIG.4

FIG.6

FIG.3

FIG.7

FIG.8

FIG.5

FIG.9

FIG.10

FIG. 1 is a front perspective view of a combined carrying bag and racket case showing our new design;

FIG. 2 is a rear perspective view thereof;

FIG. 3 is a front elevation thereof;

FIG. 4 is a top plan view thereof;

FIG. 5 is a bottom plan view thereof;

FIG. 6 is an end elevation as seen from the left of FIG. 1;

FIG. 7 is an end elevation as seen from the right of FIG. 1;

FIG. 8 is a top plan view of a modified form of the design of FIG. 1 wherein the straps and racket case have been omitted to reveal the closure;

FIG. 9 is a fragmentary front elevation of the design of FIG. 8; and

FIG. 10 is an end elevation as seen from the right of FIG. 9.

We claim:

The ornamental design for a combined carrying bag and racket case, as shown and described.
